TOP ROLLER FOR SPINNING MACHINES
Walter Sommer, Leonberg, Württemberg, Germany, assignor to SKF Kugellagerfabriken Gesellschaft mit beschränkter Haftung, Schweinfurt, Germany, a company of Germany

Filed June 27, 1957, Ser. No. 668,454
Claims priority, application Germany July 3, 1956
4 Claims. (Cl. 19—142)

This invention relates to a top roller for spinning machines, and more particularly to the kind of top roller, whereby the gap between the bearing housing or any other stationary part and a roll of the top roller is sealed so that no flying fibrous matter can enter the gap and lubricants are prevented from leaking therefrom.

The primary object of my present invention is to generally improve top rollers for spinning machines.

It is known that in top rollers as heretofore constructed the risk is very great that flying fibre particles will penetrate into the interior of the rolls of a top roller through the gap formed by the bearing housing and a roll and will reach the bearing. Fibres which have penetrated in this manner absorb the lubricant contained in the space and form in the course of time into a solid ball and impede the rotation of the rolls.

In order to preclude such fly accumulations, attempts have already been made, in various constructions, to seal off the bearings by mounting a sealing disc either on the rotating or on the non-rotating member, whereby the sealing disc was not allowed to touch the other member because this would cause a braking effect. It has been found that these sealing discs were not sufficient to protect the interior from the penetration of fluff because fine fibres penetrate even through a very narrow gap. Recently, therefore, there has been a tendency to construct the bearing housing and roll in such a manner that an angular gap was formed. In addition, in some known constructions, a groove or a cavity was provided inside the rolls, the purpose of which groove or cavity was for the penetrating fibres to collect therein.

None of the hitherto known constructions overcomes the difficulties. The lubricant is still apt to leak out, and fibres penetrate into the interior of rolls even through very narrow gaps and through angular gaps, which are conducive to the formation of fly accumulation. It is true that the aforesaid cavities permit a longer running time before the top roller has to be dismounted for cleaning, but it is impossible to prevent ball-formation of the accumulated fibres and consequential hindrance to rotational mobility of the rolls.

It is an object of the present invention to overcome the above indicated disadvantages and to provide a top roller whereby the lubricant cannot leak from the rolls to the outside and fibres cannot penetrate into the space between stationary and rotating parts.

It is a further object of the invention to provide means whereby the rolls are detachably connected to the stationary parts.

To the accomplishment of the foregoing and other objects which will appear hereinafter, my invention provides a construction which offers a satisfactory solution to the existing problems and consists in a top roller for spinning machines, that includes a pair of top rolls and comprises stationary and rotatable parts, an antifriction bearing to support the rotatable parts of each of the rolls, and a sealing ring for each roll. The rotatable parts of each roll include an outer race ring and a sleeve fitted upon the outer race ring, and the bearing includes two series of balls. In accordance with the invention, each sealing ring is shaped to sealingly engage a stationary part and the respective outer race ring and sleeve.

2

The specification is accompanied by a drawing in which: FIG. 1 is a view, partly in section, of one of two coaxial rolls of a top roller for spinning machines, illustrating an embodiment of the invention; and

FIG. 2 is a view of the sealing ring as used in the roll shown in FIG. 1.

Referring to the drawing in detail, and initially to FIG. 1, a shaft 1, at one or the inner end thereof, is rigidly mounted in a center member 2. A pivot 10 is forced onto the other or outer end of the shaft. Two such pivots, two such shafts, and the center member constitute the stationary parts of the top roller, which support the rotating parts. The assembly shown in FIG. 1 is a mirror image of the assembly not shown, the latter constituting the other roll of the top roller.

The shaft 1 is provided with two grooved raceways 3 and 4 for balls 5 and 6, respectively. Between the two series of balls, there is an intermediate ring 7 which guides a ring 8. The latter forms the outer race ring of the bearing. The axial positioning of the ring 8 is effected by an annular spring 9.

Fitted upon the outer race ring is a sleeve 12 which constitutes the roll proper, and placed around the sleeve 12 is an elastic cover 11. The sleeve 12 is shown to be wider than the outer race ring 8, so that two cavities 21 are formed between the end portions of the sleeve, the end faces of the outer race ring, and an end portion of the pivot 10 and center member 2, respectively.

A sealing ring generally identified by 13 is provided within one cavity 21. The sealing ring has substantially the shape of a Y in a lying position, when viewed in cross section, the three branches or arms of the Y being designated 14, 20, and 22. The arm 14 is of a flangelike shape, as can clearly be seen from FIG. 2, and enters the space between annular springs 15 and 16. These springs are received in matching grooves provided in the sleeve 12. At the end of the oppositely directed arm 22, there is formed a bead 17 which has axial incisions 18 (see again FIG. 2) and engages a matching recess 19 in the outer race ring 8. Arm 20 of ring 13 tapers toward the pivot 10 with which it is in circular contact.

The sealing ring is preferably made of resilient material, for instance, polyamide resins. From FIG. 1 it can be seen that the sealing ring engages the pivot 10, the outer race ring 8, and the sleeve 12. The engagements are tight so as to prevent grease from escaping from the bearing to the outside, and fibrous matter and dust from penetrating to the inside.

It is believed that the construction of my invention and the many advantages thereof will be fully understood from the foregoing detailed description.

It will be clear that a characteristic feature of the invention is that the seal takes the form of a sealing ring which is substantially Y-shaped in cross-section and is provided with three arms. One arm is mounted on the sleeve, another arm tapers toward the stationary pivot with which it is in circular contact, and the third arm terminates in a radially flexible bead which, when the sleeve is pushed over the outer race ring, comes to rest in a corresponding recess in the outer race ring which rotates with the roll. The circular contact with the pivot is made by a lip which is not likely to produce any appreciable braking effect on the roll.

In accordance with one aspect of the invention, the sleeve is positioned axially on the outer race ring of the bearing by means of the sealing ring.

A further feature of the invention consists in the fact that the arm of the sealing ring, which is mounted on the sleeve, is preferably constructed in the form of a flange and is held in a fixed position on the sleeve with the aid of annular springs.

Advantageously, the axial incisions are formed in the

bead of the sealing ring so that the desired radial flexibility is achieved.

It will be apparent that while I have shown and described my invention in a single form only, many changes and modifications may be made without departing from the spirit of the invention defined in the following claims.

I claim:

1. Top roller for spinning machines, comprising a stationary shaft, a pivot having an inner end portion and being rigidly connected to the outer end of the shaft, two series of balls, the shaft being formed as the inner ball races, a rotating outer race ring having an outer end face, a sleeve fitted upon the outer race ring and having an outer end portion extending beyond said outer end face, the inner end portion of the pivot, the outer end face of the outer race ring, and the outer end portion of the sleeve defining an annular chamber, and a sealing ring received in said annular chamber, the sealing ring, when viewed in cross section, being substantially Y-shaped and thus having three arms, one arm being interiorly mounted on the outer end portion of the rotating sleeve, one arm tapering toward the inner end portion of the stationary pivot and contacting the same circularly, and one arm terminating in a radially flexible circular bead, the outer race ring being provided on the outer end face with a recess matchingly receiving the bead, the sealing ring, on the one hand, and the outer end portion of the sleeve, on the other hand, being provided with complementary means to secure the sealing ring in its position on the sleeve.

2. In the roller according to claim 1, said complementary means including two annular springs, the outer end portion of the sleeve being interiorly provided with grooves to partly receive said springs, said first named arm of the sealing ring being formed as a flange to fit between projecting portions of the annular springs, the sealing ring being held in position on the sleeve by the first named or flange-like arm fitting between said projecting portions.

3. The roller according to claim 1, wherein the bead is formed with axially extending incisions rendering the bead

radially yielding, so that the bead will engage the recess in the outer race ring.

4. Top roller for spinning machines, including a shaft, a pivot, and a top roll, the shaft being rigidly connected at one end thereof to the pivot, the shaft and pivot constituting stationary parts, said roll including an outer race ring, a sleeve fitted upon the outer race ring, a cover placed around the sleeve, and a sealing ring substantially of Y-shape and having three arms, when viewed in cross section, the outer race ring having an outer end face, the sleeve having an outer end portion extending beyond said outer end face, the pivot having an inner end portion, the outer surface of the inner end portion of the pivot, said outer end face of the outer race ring, and the inner surface of the outer end portion of the sleeve enclosing within said roll an annular chamber to receive said sealing ring, the three arms of the Y-shaped sealing ring sealingly engaging the outer surface of the inner end portion of the pivot, the outer end face of the outer race ring, and the inner surface of the outer end portion of the sleeve, respectively, the shaft being provided with two grooved raceways to support two series of balls, the grooved raceways, the balls, and the outer race ring forming an anti-friction bearing to support the roll on its shaft, the roll further including an intermediate ring extending between the series of balls.
